UNITED STATES PATENT OFFICE

2,410,823

CALCULATING MACHINE

Jalmer M. Laiho, Skokie, Ill., assignor to Felt &
Tarrant Manufacturing Company, Chicago, Ill.,
a corporation of Illinois

Application September 17, 1941, Serial No. 411,194

40 Claims. (Cl. 235—82)

1

This invention relates in general to calculating machines, and has more particular reference to the provision of means for facilitating the use of power-driven key-responsive machines in subtractive operations.

In calculating machines of the type shown in United States Letters Patent No. 2,063,962, issued December 15, 1936, and generally in substantially all machines having actuating mechanism adapted to drive the registering or accumulating mechanism in only one direction, subtraction is performed by a process of complementary addition. For example, if it is desired to subtract "127" from the number "824," the latter is registered in the numeral wheels of the accumulator, and the nine's complement of the subtrahend less one, or the ten's complement of the units order and the nine's complement of all other orders of the subtrahend, namely, "873" is added to the minuend. This would normally leave a result of "1697" in the accumulator. In certain of the prior art machines, such as those disclosed in the patents to D. E. Felt, Nos. 767,107 and 960,528, issued on August 9, 1904, and June 7, 1910, respectively, a subtraction or carry cut-out lever is provided in association with each denominational order of accumulator mechanism, except the units order, which is selectively operable to prevent a transfer or a carry of the "10's" thereto. In this manner, the "10's" added to the left of the highest order of the minuend in subtractive operations are eliminated. In other of the prior art machines, the carry of the "10's" is allowed to take place, and "9's" are added in all orders to the left of that order in which the first figure of the subtrahend is entered, thus bringing to zero position all of the said orders. Thus, in both instances, the correct result, "697," will appear on the numeral wheels of the accumulator.

To aid the operator in quickly determining the complement of the subtrahend, it has been the practice to imprint in small figures on each key the nine's complement of the larger figure imprinted thereon, as shown in Fig. 1 of the above-mentioned U. S. Letters Patent No. 2,063,962. In the machine of the instant invention, however, the operator is completely relieved of the responsibility and mental burden of determining the complement of the subtrahend and locating it upon the keyboard when performing a subtractive operation. This is accomplished by means of a control key which, as will be more fully explained hereafter, upon depression by the operator, conditions the machine to automatically add to the minuend the nine's complement of any

2

key subsequently depressed in any denominational order higher than the units order, and to automatically add the ten's complement of the key depressed in the units order, and to add the respective complements of zero in any orders where no keys are depressed. The complementary marking of the keys is dispensed with, so there are only the large figures thereon and all chance of confusion to the operator is eliminated.

10 Heretofore, in machines of this type, the actuating movement was immediately responsive to depression of any ordinal key, but the present invention contemplates the provision of means for delaying the power action or actuating movement 15 and maintaining the keys representing the subtrahend in a depressed, or key-set, position during a subtractive operation until released, the reason for which will be made evident in the description following. In the machine of the present invention, if it is desired to subtract "20964" from the 20 number "45678," the latter is registered in the numeral wheels of the accumulator by depression of the keys bearing those figures. The machine is then conditioned for the subtractive operation by 25 a manual control, and the keys bearing the figures representing the subtrahend "20964" are then depressed and will be maintained in such position until a second control is manipulated, when the nine's complement of the first four figures 30 and the ten's complement of the units figure will be automatically added to the minuend. In other words, while the keys bearing the figures "20964" were depressed, the amount "79036" was added to the minuend, which ordinarily would 35 leave a result of "124714." However, while the complement of the subtrahend is being added to the minuend, "9's" are also being added in all orders in which no ordinal key has been depressed, so that the correct result will be obtained. In 40 other words, "9's" are added in all orders to the left of that in which the first figure of the subtrahend occurs, in order to bring all of the higher denominational wheels to zero position through a carrying operation, thereby leaving the true 45 remainder "24714."

The principal object of the invention, therefore, is to simplify subtractive operations in key-responsive calculating machines.

Another important object of the invention is 50 the provision of control means operable to render a normally key-responsive calculating machine key-set, for the purpose of enabling the complementary values of a subtrahend to be automatically entered in subtractive operations.

55 A further important object of the invention is

to eliminate the complemental indicia usually employed on the ordinal keys of calculating machines having uni-directional actuating mechanism.

Another object of the invention is the provision of means for causing entry into the accumulator of a calculating machine of the nine's complements of the values of the keys depressed in all denominational orders, except the units order, and the ten's complement of the value of any key depressed in the units order.

A further object of the invention is the provision in such a machine of means for also causing the automatic entry into the accumulator of "9's" in all denominational orders in which no 15 keys have been depressed, and "10" in the units order if no key has been depressed therein.

Another object of the invention is the provision of normally inoperative subtraction control means operable to condition a key-responsive calculating machine for a subtraction operation, together with other control means operable to cause actuation of the machine and automatic return of the subtraction control means to inoperative position.

A further object of the invention is to provide means for insuring proper sequential operation of such control means.

Another object of the invention is the provision of normally inoperative subtraction control means operable to render a key-responsive calculating machine key-set and to condition the digital actuation control mechanism to cause complemental values of the keys depressed to be entered in the accumulator.

Numerous other objects and advantages of the invention will be apparent as it is better understood from the following description, which, when taken in connection with the accompanying drawings, discloses a preferred embodiment thereof.

In the drawings:

Figure 1 is a top plan view of a calculating machine embodying my invention, showing the "minus" and "equals" keys located to the left of the several denominational orders of digital keys;

Figure 2 is a longitudinal, vertical section taken through the calculating machine shown in Fig. 1 on a plane adjacent a column of digital keys;

Figure 3 is a longitudinal vertical section taken at the left side of the calculating machine shown in Fig. 1, with parts omitted or broken away and also showing details of the accumulator mechanism;

Figure 4 is a longitudinal vertical section taken through the calculating machine of Fig. 1 showing details of a single order of actuating mechanism, with parts omitted;

Figures 5, 6, 7 and 8 are enlarged detail views of the subtraction control mechanism in various states of operation;

Figure 9 is a longitudinal vertical section taken through the calculating machine shown in Fig. 1 on a plane adjacent the overflow column and showing the subtraction control mechanism;

Figures 10, 11 and 12 are detail views of the digital actuation control mechanism.

Figure 13 is a detail view showing the construction of the digital control bar, taken along the line 13-13 of Fig. 11;

Figure 14 is a longitudinal vertical section taken through the calculating machine of Fig. 1 on a plane adjacent the overflow column and showing the digital control shifting mechanism;

Figure 15 is a transverse section taken at the 75

rear of the machine and looking toward the front thereof, with certain parts omitted to show details of the subtraction control mechanism when the machine is set for additive actuation;

Figure 16 is a similar view showing the subtraction control mechanism when the machine is set for subtractive operation;

Figure 17 is a top plan view, broken away centrally from front to back, of the calculating machine shown in Fig. 1, showing details of the arrangement of the digital actuation control mechanism and shifting means; and

Figure 18 is a detail sectional view showing the connecting means for operating the actuating mechanism of the overflow order.

For the purpose of illustrating my invention, I have shown in the drawings a key-responsive, power-driven calculating machine similar to that shown and described in Patent No. 2,063,962, hereinbefore referred to, and with some changes as subsequently shown in United States Letters Patent No. 2,018,933 issued October 29, 1935. Referring more particularly to the drawings, the calculating machine is shown as having an outer casing 21 within which the various instrumentalities of the machine are mounted on skeleton frame members or partition plates 22 disposed between the actuating mechanisms of the several denominational orders and secured together in spaced relationship at suitable points by tie-rods 23. A plurality of columns of digital keys 24, normally held in raised position by means of springs 25, are arranged to extend through a keyboard 26, positioned as part of the upper wall of the casing 21, which keys are adapted for manipulation to determine the digital degree of actuation to be imparted to the different denominational orders of accumulator mechanism. Each column of keys 24 controls the rotation of an actuator actuating pinion 28 (Fig. 2) journaled upon a transverse shaft 27 that extends across the machine and is supported by the frame members 22. Rotation of each of the actuating pinions 28 is transmitted through an internal ratchet mechanism to a combined lantern wheel and accumulator gear 26 (Figs. 3 and 4) which is also journaled on the shaft 27. The gear of the lantern wheel 28 meshes with a carrying gear 30 journaled on a shaft 29 (Figs. 3 and 4), which is disposed in parallel relationship to the shaft 27. The carrying gear also meshes with an intermediate gear 31 journaled on a transverse shaft 32, which in turn meshes with a numeral wheel pinion 33 journaled on a transverse shaft 34 and fixed to a numeral wheel 35 (Figs. 3 and 4).

Carrying mechanism is provided in each denominational order of the accumulator mechanism for the purpose of imparting a digital unit of actuation thereto each time that a ten's transfer is to take place from the next lower denominational order of the accumulator. This mechanism, as well as that hereinbefore described, is more fully disclosed in United States Letters Patent No. 1,357,747, and No. 1,357,748, issued on November 2, 1920, and includes a carrying-cam member 36 (Fig. 4), which is given a 180° rotation by a suitable carrying motor spring 37 associated with a carrying gear of the next lower denominational order for each ten's transfer that is to be effected. The carrying-cam member 36 acts upon a dolly roll secured to a bell-crank carrying-lever (not shown) to swing the latter in a clockwise direction, viewing Figs. 3 and 4. Such swinging of the carrying-lever causes a carrying pawl 41 pivotally mounted on said lever to throw

the lantern wheel and accumulator gear 28 a sufficient distance to impart, through the train of gears, a digital unit of actuation to the numeral wheel 35.

The adding is accomplished upon depression of the keys 24 and corresponding actuation of gear sectors 42 (Fig. 4) which are in mesh with the pinions 26, a said sector being associated with each denominational section of the accumulator unit in association with its controlling column of keys. The gear sectors and the control and actuating mechanism for them are duplicated for each denominational order of the calculating machine, and a general description of a single set of such mechanism will be sufficient for an understanding of them all, except that they have to be arranged and adapted to cooperate selectively and collectively with the power members.

The gear sectors 42 are mounted upon a shaft 43 which extends through the partition plates 22 of the machine, and are adapted to be moved downwardly (viewing Figs. 2 and 4) on an idle or setting stroke in amount determined by the value of the particular digital key 24 of the associated column depressed, this amount increasing in graduating steps from "1" to "9." The keys 24 in addition act through a power trip mechanism to effect a connection whereby power supplied by an electric motor, indicated generally at 44 (Fig. 3), through a power shaft 45, which is connected to the motor in any suitable manner, is effective to extend a spring 46 associated with the particular order of mechanism with which the key depressed is identified. Release of this spring thereafter accomplishes adding movement in amount determined by the particular digital key of the order depressed. Upon depression of said key, the gear sector 42 is moved through its idle or downward stroke by the power shaft 45 into position to impart proper and accurate digital accumulation to the adding mechanism upon its return movement, which is accomplished by the associated spring 46.

In the calculating machine shown in the drawings, depression of a key 24 causes its stem 47 (Fig. 2) to engage a parallel motion bar 48 which is pivoted at the front at 49 and at the rear at 51 to levers 52 and 53, respectively, which levers are pivoted in turn upon cross shafts or rods 54 and 54' extending through the partition plates 22. A link 55 is pivotally connected at 56 to the lever 52 and at 57 to the lever 53. The bar 48, levers 52 and 53 and the link 55 form part of a parallel motion device, and are constructed and mounted as shown and described in United States Letters Patent No. 2,063,962, earlier mentioned. Further and more particular description of these parts is therefore thought to be unnecessary. Each of the gear sectors 42, as stated above, is pivoted upon a cross shaft 43, and through a yielding clutch 63 is articulately connected to a hook 58 by a link 59 (the hook 58 and link 59 being articulately connected to a vertical guide member 60 which in turn is pivotally mounted on a shaft 50). Each gear sector 42 is also articulately connected to a movement controlling bar, generally shown at 61, by a pin 62 securely fixed to an arm 39 of the gear sector 42 (Fig. 4), as will be later described in detail. A spring 64 attached to lever 53 and to a tail piece 65 of a latch member 66 carried by the bar 55 normally contributes toward holding the parallel motion device in elevated position, and also holds latch member 66 in forward position for a purpose which will be presently explained. A dog 67 which is pivoted at 68

on the parallel motion bar 48 is provided with a laterally extending lug 69, which is adapted for engagement with a lug or shelf 71 on a spring-lifted lever 72 pivotally mounted on the guide member 60 with the hook 58. The operation of the parts is such that upon depression of a key 24, the stem 47 engages and depresses bar 48, imparting motion to the parallel motion device, which carries dog 67 downwardly to depress lever 72. A spring mounted on the pivot between the link 59 and the hook 58 engages the lever 72 and the hook to urge the rear end of the latter downwardly, so that it will normally cause engagement of the hook 58 with a toothed wheel 73 upon depression of lever 72. However, this spring connection between hook 58 and lever 72 will permit movement of the latter by the dog 67 relative to the hook, if the hook is restrained in its normal raised position of Figs. 2 and 4 in a manner to be later described. The toothed wheel 73 is fastened to the power shaft 45, which continually turns in a counter-clockwise direction. The engagement of the hook 58 with the wheel 73 pulls the link 59 toward the rear of the machine, or toward the left, viewing Figs. 2 and 4, which imparts downward motion to gear section 42, through the yielding clutch 63. Forward motion is thus imparted to the digital control bar 61, until one of several lugs projecting vertically therefrom, as will be hereafter more fully explained, is stopped by the stem 47 of the key 24 depressed.

The rearward motion of hook 58 and link 59, which are articulately connected to each other and to guide arm 60, causes said guide arm to pivot in a counter-clockwise direction about its shaft 50 to extend spring 46, one end of which is connected to the guide arm and the other end to a shaft or rod extending through partition plates 22. The link 59 moves the gear sector 42 downwardly on an idle stroke and into position to impart an adding movement upon release of the hook 58 and contraction of the spring 46. The downward movement of the gear sector 42 is under the control of the digital control bar 61 (Fig. 4), and the gear sector is halted when it has been moved downwardly the proper distance, enabling it upon return to impart the degree of digital advancement to the adding mechanism 50 which corresponds to the particular key depressed. The yielding clutch 63 permits the continuation of the rearward movement of the link 59 after downward movement of the gear sector 42 has been stopped, and until the end of the 55 power stroke and the automatic release of the hook 58. The release of the hook 58 is accomplished automatically in each instance, after a set increment of action has been imparted to the link 59, by the teeth of the wheel 73. Upon the 60 return stroke (the operative stroke of the gear sector), the yielding clutch 63 permits relative movement of the parts in reverse direction to the beginning of the adding movement, and thereafter the adding actuation is accomplished.

65 It is apparent, therefore, that upon depression of a key 24, the digital control bar 61 determines the degree and extent of the downward movement of the gear sector 42, and the bar 48 accomplishes connection of the latter to the power 70 mechanism. Means are provided to prevent return movement of the dog 67 before the hook 58 has opportunity to fully engage the toothed wheel, which means comprise latch member 66 which is pivoted at 74 on link 55. This latch 75 member has an engaging arm 75 which is adapted

to engage upon the laterally projecting end 76 of the dog 67 to hold the dog down against return upward movement and the parallel motion device in depressed position. Just prior to the release of the hook 58, a pin 77 in an upwardly extending arm 78 of vertical guide member 60, which through its connection with hook 58 has been carried rearwardly, engages a finger 79 of latch member 66 and frees the dog 67 so that the parallel motion device may return to normal raised position. In this operation, the key 24 which has been operated is held depressed until release of the hook 58 from the wheel 73, when the key will be released and returned to normal raised position. A bar 81 having rearwardly extending pointed locking lugs or teeth 82, is pivoted upon studs 83 and 83' extending through slots 84 and 84' in bars 48 in each denominational order of the machine. Consequently, upon depression of a key 24, bar 81 is moved rearwardly (to the left viewing Fig. 2), relative to key stems 87. Referring more particularly to Figs. 15 and 16, each key stem is provided adjacent its lower end with an aperture 85 extending therethrough into which the tooth 82 enters in the rearward movement of the bar 81, thus holding the key down until the parallel motion device is released and the parts returned to normal elevated position. It will be understood that, while no two keys 24 of the same column or denominational order may be operated simultaneously, as described in Patent No. 2,043,021 issued June 2, 1936, any key of one order may be operated at the same time as any desired key of any other denominational order or orders.

The present invention contemplates the provision of means for facilitating subtractive operations by conditioning the machine to automatically control the digital actuation of the actuating mechanism therein in accordance with the complemental value of the keys depressed in entering the subtrahend. Such means completely eliminate the heretofore dual marking of the keys in accordance with the nine's complemental value thereof, thus relieving the operator of the mental burden connected with determining the complemental value of the subtrahend. In the exemplary embodiment, after the machine is conditioned for a subtractive operation, the keys representing the figures of the subtrahend are depressed and maintained in such position, and the actuating movement is delayed until a second control key is depressed which automatically causes the complement of the depressed keys representing the subtrahend to be added to the minuend in the accumulator. Further, simultaneously with the adding of the complement of the subtrahend, "9's" are added in all denominational orders in which no key has been depressed, except the units order in which "10" is added if no key therein has been depressed, for a purpose which will be more fully explained hereafter.

The subtraction control device in its preferred form comprises a set of keys including "minus" and "equals" control keys 86 and 87, respectively, (Figs. 1, 5, 6 and 7) located to the left of the ordinal series of keys 24 for convenient access. The keys are provided with the usual stems 88 extending through the keyboard 25 and are normally held in raised position by springs 288.

The lower portion of stem 88 of "minus" key 86 is in engagement with a parallel motion bar 89 which is a modified form of the parallel motion bars 48 earlier described. The arrangement 78

and construction of the parallel motion bar 89 is similar to that of bar 48, so that further description thereof is not thought to be necessary, the parts of the parallel motion device 89 being given reference numerals having the last two figures the same as those given to similar parts of the bar 48, and preceded by the figure "2." Depression of "minus" control key 86 and parallel motion device 89 causes forward movement (to the right viewing Figs. 5 and 6) of the link 255, and allows arm 275 of latch member 266 to engage the laterally projecting end 276 of dog 287, which is pivoted at 268 on parallel motion device 89, to hold the parallel motion device in depressed position. The key 86 is also maintained in depressed position by a tooth 91 formed on a bar 92 which is pivoted upon studs 283 and 283' extending through slots 284 and 284' in the bar 89. Upon depression of key 86, the bar 92 is moved rearwardly (to the left viewing Figs. 5 and 6), allowing tooth 91 to enter the aperture 285 in the key stem 88. The bar 92 is also provided with a vertical projection 93 adapted normally to underlie the stem 88 of the "equals" key 87, for a purpose to be later described.

As has already been mentioned, it is necessary that the actuating action be not immediately responsive to depression of the ordinal keys 24, as is normally the case, and that the keys representing the subtrahend be maintained in a depressed position when a subtractive operation is being performed. To this end, therefore, means are provided, which are operable at the will of the operator, for preventing immediate engagement of hooks 58 with toothed wheels 73 upon depression of ordinal keys 24. These means are under the control of the "minus" key 86 which, upon depression, engages an upwardly extending arm 94 (Figs. 7 and 8) of a lever 95 which is also provided with a downwardly and forwardly extending arm 96. The lever 95 is pivoted at 97 on a pin fixed to an intermediate plate 22, and is normally maintained under tension of a spring 98 in its upward position, as shown in full lines in Fig. 8, where further upward movement is limited by a vertical lug 99 formed on arm 94 contacting the under surface of the bottom plate of the keyboard 25. Engagement of stem 88 of "minus" control key 86 with arm 94 rocks the lever 95 in a clockwise direction with a consequent downward movement of arm 96, as shown in Fig. 7. Pivoted to the lower end of arm 96 is a pawl 100 which is provided with a downwardly extending arm 101, a rearwardly extending horizontal arm 102 and an upwardly extending arm 102. The pawl is normally urged in a counter-clockwise direction (viewing Figs. 7 and 8) by a spring 103, and such movement is limited by engagement of arm 101 with a pin 104 secured to the arm 96. The lower arm 102 is normally positioned above a pin 105 in an arm 106 which is securely fastened to a transverse rock shaft 107. Located upon the shaft 107 and also securely fastened thereto are lock arms 108 (Figs. 4, 5, 6 and 17), one for each denominational order of the machine, and each of which is provided with a laterally extending lug 109 adapted, upon depression of control key 86 and consequent counter-clockwise rotation of rock shaft 107, to engage an associated vertical lug 111, one of which is struck up from each of the hook members 58. The lock arms 108 are normally held in upward disengaging position under tension of a spring 100, which normally maintains shaft 107 in the full line position of Figs. 7 and 8.

It will be readily apparent, however, that depression of "minus" key 86 will, through arm 96 and pawl 98, cause shaft 107 to rock, allowing lugs 109 of all of the lock arms 108 to engage their respective lugs 111 of hooks 58. The parts are maintained in such locking engagement during subsequent depression of ordinal keys representing figures of the subtrahend, which, as previously explained, would normally result in a power action through engagement of hook 58 with toothed wheel 73, and until released by depression of the "equals" key 87, as will be hereafter more fully explained. As earlier described, upon depression, the ordinal keys 24 are momentarily held depressed by engagement of tooth 82 with aperture 85 until the parallel motion device 48 is allowed to rise, when pin 77 of vertical guide member 60 releases latch 66, freeing dog 67. Until engagement of the hooks 58 with their toothed wheels 73 is allowed to take place, therefore, it will be readily understood that the keys 24 depressed in entering the subtrahend will be maintained in such key-set position until the hooks 58 are released from lock arms 108 and allowed to drop into engagement with toothed wheels 73, and dog 67 has been released from latch member 66 to return the parallel motion device and keys 24 to normal elevated position.

Means are also provided to automatically control the digital actuation of the adding mechanism in accordance with the nine's complemental value of the keys depressed in entering a subtrahend in all denominational orders except the units order, in which the ten's complemental value of the key depressed is added. In other words, in performing a subtractive operation, the keys used in such calculation have only single value indicia inscribed on their top surfaces, the complemental value of such keys depressed in entering the subtrahend being automatically determined and added to the minuend by means now to be described. The mechanism controlling the digital actuation of the adding mechanism in each denominational order is indicated generally at 61 (Fig. 11) and comprises a regular stop bar 112 and a complemental stop bar 113, secured together and spaced relative to each other by means of studs 114 (Figs. 10 and 13). The bars 112 and 113 have formed thereon vertically projecting stop lugs 115, the lugs 115 of the stop bar 112 being spaced progressively further back of the key stems from the front to the rear of the machine, and the lugs 115 of stop bar 113 being spaced progressively further back of the key stems from the rear to the front of the machine (as shown in Figs. 4, 10, 11 and 14). The stop lug 115 of the regular stop bar 112 just to the rear of the "1" key is spaced one step back of the "1" key, and the distance from each succeeding stop lug to its associated key stem toward the rear of the machine gradually increases until the rearmost lug is spaced nine steps back of the "9" key. The stop lug of the complemental stop bar 113 just to the rear of the "1" key is spaced eight steps back of the "1" key and the spacing gradually decreases until the lug back of the "8" key is spaced one step therefrom and the last stop lug is just even with the "9" key.

It has been earlier explained that in machines of this type it has been the necessary practice in entering the subtrahend to enter one less in the units order, or, in other words, to strike the nine's complement of all orders except the units order, in which the ten's complement was entered to obtain the correct result. Means have

been provided in the present invention to automatically control the digital actuation of the accumulator mechanism in the units order in accordance with the ten's complement of the key depressed, or, if no key has been depressed, to automatically add "10" in such order to bring about the correct result. This is accomplished by an arrangement or spacing of the stops on the ten's complemental stop bar 113' of the units order (as shown in Fig. 12), different from that of the nine's complemental stop bar 113 in all other orders. In other words, the stops 115 on the ten's complemental stop bar 113' of the movement controlling bar 61 in the units order (Figs. 10 and 12) are spaced progressively one step further back than are the stops 115 on the nine's complemental stop bars 113. The gear sector in the units order therefore is given a relatively greater adding movement by the ten's complemental stop bar 113' than are the gear sectors of all other higher denominational orders under the control of their complemental stop bars 113. The complemental stop bars 113 and 113' are each provided at their forward ends with depending arms 116 having a bifurcated portion adapted to embrace the pin 62 located in the upwardly extending arm 39 of the associated gear sector 42 (Figs. 4 and 14). As has already been described, in normal operation, upon depression of an ordinal key 24 and engagement of the clutch hook 58 with the toothed wheel 73, there is a consequent downward movement of gear sector 42 which, through its connection with the digital control bar 61, as just explained, is halted by engagement of the associated stop lug 115 on the stop bar 112 with the stem 47 of the depressed key. The resulting movement is thus just sufficient to add into the accumulator an amount represented by the value of the key depressed.

Means are provided, when desiring to enter the complement of the subtrahend during a subtractive operation, for shifting the complemental stop bars 113 and 113' into operative relation with the ordinal series of keys, so that upon depression of a key and subsequent downward movement of the gear sector 42, the complemental value of the key depressed will be added into the accumulator, as distinguished from the actual value of the key depressed when the regular stop bar 112 is in operative relation therewith. The lower portion of stem 88 of the subtraction control "minus" key 86 is provided with an angular surface in engagement with a roll 118 which is rotatably secured to an upright arm 119 (viewing Figs. 14, 15 and 16). The arm 119 is fixedly secured to a rock shaft 121 running from front to rear of the machine (Figs. 14 and 17), and having a bearing in the lateral faces 122 and 122' provided in the upper portion of vertical support pieces 117 and 117', which are in turn pivotally supported on the tie rods 23. Also securely fixed to the rock shaft 121 are upright arms 123 and 124, located adjacent the front and rear of the machine, respectively (Fig. 14). The upper free portion of the arm 123 is disposed in a small slotted portion 120 of a transverse support bar 125 positioned near the front of the machine (Figs. 10, 14 and 17), which is slidably mounted in the intermediate frame plates 22 and is provided with a plurality of laterally spaced, upstanding pins 126 fixed therein. The pins 126 are adapted to enter the open portion between the stop bars 112 and 113 of the digital control bars 61 to maintain proper alignment thereof.

with respect to the key stems 47. A similar transverse support bar 121 is mounted at the rear of the machine, and formed thereon is a forwardly extending, slightly offset horizontal arm (Figs. 10 and 14) provided at its forward end with a small slotted portion 120', similar to the slotted portion 120 in the transverse support bar 125, in which is positioned the upper portion of the upright arm 124. The bar 121 is also provided with pins 126' adapted to be embraced by the open portion of the digital control bars 61 to maintain proper alignment of the rear ends thereof with respect to the key stems 47. The rock shaft 121 and the support bars 125 and 127 and digital control bars 61 are normally maintained in the position of Fig. 15 under tension of a spring 130 interconnected between the lower end of the arm 123 and a frame plate 22 to retain the regular stop bars 112 in operative relationship with their associated digital key stems.

With such an arrangement, it will readily be perceived that upon depression of the "minus" control key 86, the resulting movement of arm 119 to the left (viewing Figs. 15 and 16) will cause the shaft 121 to be rocked counter-clockwise to shift the support bars 125 and 127 to the left, through the medium of upright arms 123 and 124. The digital control bars 61, supported by the bars 125 and 127, will similarly be shifted to position the stop bars 113 and 113' in operative relation with the stop portions 19 of the key stems 47. It will be apparent that when either of the stop bars 112 or 113 is in operative relation with the stop portion 19 of the ordinal key stem, the other stop bar is completely out of operative relation therewith. This is accomplished by means of a slot 40 which is cut in the lower portion of each of the key stems 47 and is adapted to be in alignment with the stop bars 113 and 113' when the stop bars 112 are in effective or operative position relative to the key stems 47, as shown in Fig. 15. When the stop bars 113 and 113' are in effective or operative position relative to the key stems 47, then the stop bars 112 will pass freely by the stop portions 19 at the left of the key stems, as viewed in Fig. 16.

As has been previously described, the parallel motion bar 89 and "minus" control key 86 are maintained in depressed position after actuation of the latter, and lock arms 108, in conjunction with the vertical lugs 111, are in position to prevent engagement of hooks 58 with the toothed wheels 73, which otherwise would result in an actuating movement upon depression of an ordinal key when entering the subtrahend in a subtractive operation. The ordinal keys depressed in entering the subtrahend are maintained in such depressed or key-set position following depression of the "minus" control key 86, and the parallel motion bars of the respective orders cannot return to normal because of the lateral ends of their dogs 67 having been engaged by the associated latch members 66, which remain in such engaged position until a power action takes place, as earlier described.

Means are also provided, therefore, for releasing the clutch hooks 58, after the subtrahend has been set upon the keyboard, to enable their engagement with the toothed wheels 73 to allow the complement of the subtrahend to be added into the accumulator mechanism to complete the subtractive calculation. The means for accomplishing this is under the control of the "equals" key 87, the stem 88 of which is in engagement with a lever 128 (Figs. 7 and 8) which

is provided with a hub portion 129 pivoted on a short shaft 131 fixed to an intermediate frame plate 22. The lever 128 is provided adjacent its rearward end with a downwardly extending arm 132, to the lower extremity of which is securely fixed a pin 133 adapted for engagement with the upwardly extending arm 102 of pawl 98. The pawl 98 is rocked in a clockwise direction, viewing Figs. 7 and 8, against the tension of its spring 103, upon depression of the "equals" key 87. Such clockwise movement of the pawl 98 causes its lower arm 99 to be swung rearwardly to be disengaged from pin 105 of arm 106, allowing the shaft 107 to be rocked clockwise under the tension of its spring 100. The lock arms 108 are thus removed from locking engagement with the lugs 111 formed on the hooks 58, thereby allowing those hooks 58 in the denominational orders in which digital keys have been depressed in the previous setting of the subtrahend into the keyboard to drop into engagement with their toothed wheels 73 (Fig. 7).

As has been mentioned, it is necessary that "9's" be added in all denominational orders in which no digital key has been depressed, and that "10" be added in the units order if no key has been depressed therein, for the purpose already explained. To accomplish this, the lever 128 is provided at its forward end with a second downwardly extending arm 134 provided with a bifurcated lower portion 135 embracing a pin 136 fixed in the curved upper end of a lever 137. The lever 137 is securely fixed to a transverse rock shaft 138 and is urged in a rearward or counter-clockwise direction, viewing Figs. 7 and 8, under tension of spring 140. Also securely fixed to the rock shaft 138 are a plurality of upright arms 139, spaced transversely across the machine in each denominational order thereof, the upper extremities of said arms being in engageable relationship with pins 141 in links 55 (Fig. 2). Depression of the "equals" key 87, as has already been described, rocks lever 128 upon its pivot, thus swinging its forward arm 134 upwardly to rock the shaft 138 forwardly. Such movement also swings all of the arms 139 forwardly, thereby urging the links 55 in a forward direction. Movement of any of the links 55 in this manner imparts motion to the associated parallel motion device to cause depression of the hook 58 controlled thereby into the path of its associated toothed wheel 73, which results in an adding actuation in that denominational order. Movement of the parallel motion device not having resulted from depression of a digital key 24 in such order, it will be readily apparent that bar 61 which controls the digital setting of the gear sector 42 will receive full forward movement, with a consequent maximum downward movement of the gear sector sufficient to add "9" into the accumulator upon the upstroke of the sector under tension of spring 46. When no key has been depressed in the units order, that is, when a zero occurs in the units order of the subtrahend, forward swinging of the arm 139 therein will likewise cause maximum downward movement of the gear sector 42, but the resultant upstroke by the spring 46 will add "10" into the units order of the accumulator, rather than the "9's" added in the other orders in which no keys were depressed.

In machines in which the present invention is embodied, there is usually provided an "overflow" numeral wheel 160 (Fig. 1) to which is transferred the carry of the "10's" resulting from

operation of the actuating mechanism in the last or highest denominational order. Formerly, in such machines, a subtraction or carry cutout lever was provided in association with each denominational order of accumulator mechanism which was selectively operable to prevent a transfer or a carry of the "10's" thereto from a lower denominational order. The present invention, however, contemplates the provision of actuating mechanism in the overflow order for automatically adding the value of "9" to the accumulator mechanism of that order to bring to zero position the numeral wheel of that order when a "1" has been carried thereto by the entering of the complementary value of the subtrahend and the subsequent carrying of the "9's" across the register as just described. To this end there is provided a sector 242 (Fig. 9) similar to the sectors 42 already described and mounted on the shaft 43, but directly connected to the guide member 260 by means of a link 259, which is pivotally connected to the sector 242 at 142 and to guide member 260 at 143. A spring 246 connected at 144 to guide member 260 and to a rod extending through the intermediate frame plates 22 at 145 normally serves to maintain the guide member 260 and gear sector 242 in the position of Fig. 9. Rearward movement of the guide member 260 will, through the link connection 259, cause the actuating sector 242, to be moved downwardly in its idle or setting stroke, and spring 246 will return it to normal raised position in an adding movement in the manner previously explained, relative to the regular sectors 42.

Rearward movement of the guide member 260 in the overflow order is accomplished through connection with the guide member 60 of the next lower denominational order, or that order to the right (viewing Figs. 1 and 18) of the overflow order. Upon forward movement of link 255 when parallel motion bar 89 is depressed by "minus" control key 86, a pin 146 fixed to the link 255 urges forwardly an upright arm 147 with which it is normally in engagement (Figs. 5, 6 and 9). The upright arm 147 is part of a lever 148 mounted upon a short shaft 149 and urged in a counter-clockwise direction under tension of a spring 151 (Fig. 5). The lever 148 is also provided with a downwardly and forwardly extending arm 152 in the forward extremity of which is located a pin 153 in engagement with the upper surface of a lock piece 154. The lock piece 154 is pivotally secured at 155 to a horizontal arm 156 formed on vertical arm 278 of guide member 260 in the overflow order (see also Fig. 18), and extends rearwardly and is offset into the next lower denominational order where it is adapted to overlie a pin 157 secured to the guide member 60 of that order. The lock piece 154 is normally maintained in its disengaged position of Figs. 5, 8 and 9 under the tension of spring 158. Upon depression of "minus" key 86, however, and forward movement of link 255, the lever 148 is rocked in a clockwise direction urging the lock piece 154 into engagement with pin 157 of the guide member 60 of the next lower order, where it is maintained until parallel motion bar 89 is released and allowed to rise to normal position. Upon engagement, therefore, of hook member 58 with toothed wheel 73 in the denominational order to the right of the overflow order, either resulting from setting of a digital key 24 therein and/or depression of the "equals" control key 87 and release of lock arms 108 as already ex-

plained, the guide member 60 in that order will be pulled rearwardly and, by its connection with guide member 260 of the overflow order through the lock piece 154, the gear sector 242 of the overflow order will be given a maximum downward movement to add "9" upon its upward movement under the action of spring 246.

As the guide member of the overflow order is moved rearwardly as just described, pin 271 located in the upward extension of vertical arm 278 of the guide member 260 engages finger 279 on the latch 266 to swing the latch member in a clockwise direction from its operative position of Fig. 6. The dog 267 is thus freed from arm 275 of the latch 266 to allow parallel motion bar 89 to return to its normal raised position to remove tooth 91 from aperture 285 in the stem 88 of key 86. While this release of latch 266 will normally allow the associated spring 238 to return the "minus" key 86 to its upper or inoperative position, such operation cannot take place unless downward pressure has been removed from the "equals" key 87 and the latter has been returned to inoperative position by its spring 238 to remove the stem 88 thereof from the path of movement of the projection 93 on bar 92.

Means are provided for preventing the relatching in a depressed position of parallel motion bar 89 and "minus" key 86 if the "equals" key 87 is allowed to rise while key 86 is still being held depressed by the operator, or if the "equals" key 87 is held down by the operator. To this end, there is provided a forwardly extending arm 159 on latch 266 of the overflow order which is adapted to engage the face of a lip or lug 161 formed at the extremity of a vertical lever 162 (as shown in Figs. 5, 6, 7 and 9). The lever 162 is moved slightly forward against the tension of its spring 163 by the arm 159 when parallel motion bar 89 is depressed by the "minus" key 86, and link 255, to which the latch 266 is pivoted, is moved forwardly. Subsequent operation of the "equals" control key 87 causes rearward movement of the guide member 260 of the overflow order, as already described, whereupon pin 271 of guide member 260 engages the finger 279 of latch member 266 to swing the latter in a clockwise direction from its position of Fig. 6 to its position of Fig. 7. In such movement of the latch 266, the arm 159 thereof is swung beneath the lip or lug 161 on the lever 162, and the latter is moved rearwardly in a counter-clockwise direction by its spring 163 to maintain the latch 266 in inoperative position. In this position, the downwardly extending arm 275 of the latch 266 is to the rear of projection 276 of dog 267, and the dog cannot be relatched in such position until the parallel motion bar 89 has been allowed to return to its upper or normal position and has again been depressed by the "minus" key 86. Thus the subtractive control devices are compelled to return to normal position after a subtractive operation, and the machine is automatically conditioned for additive operation.

Means are also provided to insure the proper sequence of depression of keys 86 and 87, respectively. This means comprises bar 92, earlier described, and its stop 93. In the normal or inoperative position of Fig. 5, stop 93 is directly beneath the lower surface of stem 88 of the "equals" key 87 to effectively prevent depression of the "equals" key 87 before the "minus" key 86 is depressed. Upon depression of key 86, however, the bar 92 is moved rearwardly to the position of Fig. 6, due to its pivotal mounting upon the paral-

15

lel motion bar 89, and the stop 93 is removed from the path of the key 87 to permit depression thereof.

It will thus be seen that in order to perform a subtractive operation with the instant machine, after the minuend has been entered into the accumulator in the usual manner, the operator merely depresses the "minus" control key 86, then depresses the digital keys 24 whose indicia represent the true value of the subtrahend, and finally depresses the "equals" control key 87. Consequently, it is unnecessary for the operator to mentally compute the complemental value of the subtrahend, or to remember to employ the small figures usually provided on the ordinal keys when entering the same. Depression of the "minus" key 86 will condition the normally key-responsive mechanism for key-set actuation by engaging the lock arms 108 with the lugs 111 of all of the hooks 58 to prevent depression of the latter into engagement with their toothed wheels 73 upon subsequent depression of any of the ordinal keys 24 in the setting of the subtrahend into the keyboard. Depression of the "minus" key 86 also conditions the digital actuation control mechanism to cause complemental values of the keys subsequently depressed to be entered in the accumulator, by shifting all of the digital control bars 61 laterally to move the regular stop bars 112 out of operative relationship, and the complemental stop bars 113 and 113' into operative relationship, with the stems of the ordinal keys 24. Depression of the "equals" key 87, after the true subtrahend has been set into the keyboard, causes operation of the actuating mechanism, including all of the gear sectors 42, by moving all of the lock arms 108 to inoperative position to release the hooks 58 and permit engagement of the same with their toothed wheels 73. Depression of the "equals" key 87 also rocks the arms 139 forwardly to cause engagement of the hooks 58 with their toothed wheels 73 in all of the other denominational orders of the machine in which no digital keys have been depressed, so that "9's" will be entered in such orders of the accumulator, or "10" in the units order if no key therein has been depressed. Since the prior depression of the "minus" key 86 has lowered the lock piece 154 of the overflow order into engagement with the pin 157, depression of the "equals" key 87 also causes operation of the gear sector 242 to enter "9" in the overflow order of the accumulator. The correct result will thus be assured, and the bar 92, parallel motion bar 89, dog 267, latch member 266, together with its arm 159 and the lever 162, will insure proper sequence of operation of the keys 86 and 87.

It is thought that the invention and its attendant advantages will be understood from the foregoing description, and it will be apparent that various changes may be made in the form, construction and arrangement of the parts without departing from the spirit and scope of the invention or sacrificing all of its material advantages, the form hereinbefore described and illustrated in the drawings being merely a preferred embodiment thereof.

I claim:

1. In a normally key-responsive calculating machine having digital control keys, an accumulator, and mechanism for actuating said accumulator in accordance with the values of, and in response to the depression of said keys; control means for rendering said key-responsive mechanism key-set, and means operable by said first

16

means for conditioning said mechanism to actuate said accumulator in accordance with the complemental values of the keys depressed.

2. In a calculating machine having an accumulator, denominational orders of actuators for said accumulator, keys for controlling said actuators, means for driving said actuators, power means, means for connecting said power means and said driving means, and denominational stop bars for determining the digital actuation of said actuators in accordance with the values of the keys depressed; normally ineffective stop bars for determining the digital actuation of said actuators in accordance with the value of the nine's complement of the keys depressed in all denominational orders higher than the units order, another normally ineffective stop bar for determining the digital actuation of said actuator in accordance with the value of the ten's complement of the key depressed in the units order, a first subtraction control key, means operable by said first subtraction control key for shifting said two named normally ineffective stop bars into effective relationship with said keys, means operable by said first subtraction control key for preventing connection between said power means and said driving means, a secondary subtraction control key, and means operable by said secondary subtraction control key for subsequently effecting said connection to add the said complemental values in all denominational orders in which a key has been depressed and to add "10" in the units order if no key has been depressed therein and to add "9's" in all other denominational orders in which no key has been depressed.

3. A calculating machine comprising an accumulator, denominational orders of actuating mechanism for said accumulator, keys for controlling said actuating mechanism, means for driving the actuating mechanism, power means, means for connecting said power means and said driving means; a first calculation control key, means operable by said first calculation control key for preventing connection between said power means and said driving means when a said key is subsequently depressed, a second calculation control key, means operable by said second calculation control key to overcome said preventing means and allow said connection to take place, and means operable by said second calculation control key for automatically causing said actuating mechanism to add "10" in the units order if no key has been depressed therein and to add "9's" in all other denominational orders in which no key has been depressed.

4. A calculating machine, comprising accumulator mechanism, actuating mechanism therefor, keys for controlling said actuating mechanism, means for driving said actuating mechanism, power means, means for connecting said power means and said driving means, means for controlling the digital actuation of said actuating mechanism in accordance with the values of the keys depressed, normally ineffective means for controlling the digital actuation of said actuating mechanism in accordance with the complemental values of the keys depressed, means for rendering said last means effective and for preventing connection between said power means and said driving means, and means for subsequently effecting said connection to add the said complemental value in all denominational orders in which a key has been depressed, and to add "10" in the units order if no key has been depressed therein

and to add "9's" in all other denominational orders in which no key has been depressed.

5. In a calculating machine, a plurality of ordinal columns of keys corresponding to the digits 1 to 9, inclusive, a multi-denominational register, a multi-denominational register actuator each denominational element of which is responsive to one ordinal column of digit keys, ordinal digit stop bars which limit the motion of the actuator; a tens-complementary digit stop bar associated with the lowest denominational element of the register actuator, ordinal nines-complementary digit stop bars associated with all other denominational elements of the register actuator that are responsive to a column of digit keys, a primary subtraction control key, means to hold said primary subtraction control key in depressed position, means operable by said primary subtraction control key to replace said ordinal digit stop bars by their respective complementary digit stop bars, means operable by said primary subtraction control key to detain each denominational element of the register actuator from operation while values are set up on the ordinal columns of digit keys, a secondary subtraction control key, means operable by said secondary subtraction control key to set all denominational elements of the register actuator in readiness for operation if not previously set by operation of the digit keys in their respective ordinal columns, means operable by said secondary subtraction control key to release said register actuator detaining means to subtract the value set up on the ordinal columns of digit keys from the register by adding the complementary values corresponding to the digit keys depressed and adding "9's" in all columns where no digit key is depressed and "10" in the lowest denominational column if no key was depressed in that column, and means to release the primary subtraction control key from depressed position after the secondary subtraction control key has returned to non-depressed position.

6. In a calculating machine, a plurality of ordinal columns of digit keys, a multi-denominational register, a multi-denominational register actuator each denominational element of which is responsive to one ordinal column of digit keys, stops to limit the maximum motion of each element of the register actuator to nine units except the lowest denominational element which may have a maximum motion of ten units, ordinal digit stop bars which limit the motion of the elements of the register actuator when intercepted by the depressed digit keys; a tens-complementary digit stop bar associated with the lowest denominational element of the register actuator, ordinal nines-complementary digit stop bars associated with all other denominational elements of the register actuator that are responsive to a column of digit keys, a primary subtraction control key, means operable by said primary subtraction control key to replace said ordinal digit stop bars by their respective complementary digit stop bars, means operable by said primary subtraction control key to detain each denominational element of the register actuator from operation while values are set up on the ordinal columns of digit keys, means to hold said primary subtraction control key in depressed position, a secondary subtraction control key, means operable by said secondary subtraction control key to set all denominational elements of the register actuator in readiness for operation if not previously set by operation of the digit keys

70
75

in their respective ordinal columns, means operable by said secondary subtraction control key to release said register actuator detaining means thereby to subtract the value set up on the ordinal columns of digit keys from the register by adding the complementary values determined by each element of the register actuator receiving its maximum motion unless its complementary digit stop bar is intercepted by a depressed digit key, and means to release the primary subtraction control key from depressed position after the secondary subtraction control key has returned to non-depressed position.

7. In a calculating machine, a plurality of ordinal columns of digit keys, a multi-denominational register, a multi-denominational register actuator each denominational element of which is responsive to one ordinal column of digit keys, stops to limit the maximum motion of each element of the register actuator to nine units except the lowest denominational element which may have a maximum motion of ten units, ordinal digit stops which limit the motion of the elements of the register actuator to the values of the digit keys depressed; tens-complementary digit stops associated with the lowest denominational element of the register actuator, ordinal nines-complementary digit stops associated with all other denominational elements of the register actuator that are responsive to a column of digit keys, a primary subtraction control key, means operable by said primary subtraction control key to replace said ordinal digit stops by their respective complementary digit stops, means operable by said primary subtraction control key to detain each denominational element of the register actuator from operation while values are set up on the ordinal columns of digit keys, means to hold said primary subtraction control key in depressed position, a secondary subtraction control key, means operable by said secondary subtraction control key to set all denominational elements of the register actuator in readiness for operation if not previously set by operation of the digit keys in their respective ordinal columns, means operable by said secondary subtraction control key to release said register actuator detaining means thereby to subtract the value set up on the ordinal columns of digit keys from the register by adding the complementary values determined by each element of the register actuator receiving its maximum motion if its motion is not limited by the complementary digit stops cooperating with depressed digit keys, and means to release the primary subtraction control key from depressed position after the secondary subtraction control key has returned to non-depressed position.

8. In a calculating machine, a keyboard, a multi-denominational accumulator, a multi-denominational accumulator actuator, stops to limit the maximum motion of each denominational element of the accumulator actuator to nine units except the lowest denominational element which may have a maximum motion of ten units, ordinal digit stops which limit the motion of the elements of the accumulator actuator according to the digit values set up on the keyboard, tens-complementary digit stops associated with the lowest denominational element of the accumulator actuator, ordinal nines-complementary digit stops associated with all other denominational elements of the accumulator actuator, a primary subtraction control key, means operable by said primary subtraction control key to replace said ordinal digit stops by their respective complementary

digit stops, means operable by said primary subtraction control key to detain each denominational element of the accumulator actuator from operation while values are set up on the keyboard, means to hold said primary subtraction control key in depressed position, a secondary subtraction control key, means operable by said secondary subtraction control key to set all denominational elements of the accumulator actuator in readiness for operation if not previously set by operation of the keyboard, means operable by said secondary subtraction control key to release said accumulator actuator detaining means thereby to subtract the value set up on the keyboard from the accumulator by adding the complementary values determined by each element of the accumulator actuator receiving its maximum motion if its motion is not limited by the complementary digit stops cooperating with the digit values set up on the keyboard, and means to release the primary subtraction control key from depressed position after the secondary subtraction control key has returned to non-depressed position.

9. In a calculating machine, a plurality of ordinal columns of digit keys, a multi-denominational register, a register actuator comprising a series of denominational elements, stops to limit the maximum motion of each denominational element of the register actuator to nine units except the lowest denominational element which may have a maximum motion of ten units, ordinal digit stop bars which limit the motion of the actuator elements to amounts corresponding to the values of the keys depressed, a normally ineffective ordinal tens-complementary digit stop bar associated with the lowest denominational element of the register actuator, normally ineffective ordinal nines-complementary digit stop bars associated with all other denominational elements of the register actuator, a primary subtraction control key, means operable by said primary subtraction control key to shift said ordinal digit stop bars out of cooperative relationship with said digit keys and to shift the respective complementary digit stop bars into cooperative relationship with said digit keys to limit subsequent motion of the register actuator elements to amounts proportional to the complementary values of the digit keys depressed, means operable by said primary subtraction control key for detaining each denominational element of the register actuator from operation while values are set up on the ordinal columns of digit keys, a secondary subtraction control key, means operable by said secondary subtraction control key for setting all denominational elements of the register actuator in readiness for operation if they were not previously set by operation of the digit keys, and means operable by said secondary subtraction control key for releasing said register actuator detaining means whereby to cause all elements of said register actuator to add the complementary values of the digit keys depressed or their respective complements of zero in denominational orders where no digit keys were depressed.

10. In a calculating machine, a plurality of ordinal columns of digit keys, a multi-denominational register, a register actuator comprising a series of denominational elements each responsive to one ordinal column of digit keys, ordinal digit stop bars each capable of being intercepted by a depressed digit key to limit the motion of its respective actuator element to an amount proportional to the digit value of the key depressed, an ordinal tens-complementary digit stop bar asso-

ciated with the lowest denominational element of the register actuator, ordinal nines-complementary digit stop bars associated with all other denominational elements of the register actuator, a primary subtraction control key, means for holding said primary subtraction control key in depressed position, means operable by said primary subtraction control key to replace said digit stop bars by said complementary digit stop bars, means operable by said primary subtraction control key for preventing each denominational element of the register actuator from operating while values are set up on the ordinal columns of digit keys, a secondary subtraction control key, means operable by said secondary subtraction control key for setting all denominational elements of the register actuator in readiness for operation if not previously set by operation of the digit keys in their respective ordinal columns, means operable by said secondary subtraction control key for releasing said register actuator preventing means to subtract the value set up on the ordinal columns of digit keys from the register by adding the complementary values corresponding to the digit keys depressed and the respective complements of zero in all columns where no digit key is depressed, and means for releasing the primary subtraction control key from depressed position after the secondary subtraction control key has returned to non-depressed position.

11. In a calculating machine, a keyboard, a multi-denominational accumulator, an accumulator actuator comprising a series of denominational elements each responsive to the keyboard, stops to limit the maximum motion of each denominational element of the accumulator actuator to nine units except the lowest denominational element which may have a maximum motion of 10 units, ordinal digit stops which limit the motion of the actuator elements to amounts proportional to the values set up on the keyboard, ordinal tens-complementary digit stops associated with the lowest denominational element of the accumulator actuator, ordinal nines-complementary digit stops associated with all other denominational elements of the accumulator actuator, a primary subtraction control key, means operable by said primary subtraction control key to shift said ordinal digit stops to ineffective position with respect to said accumulator actuator elements and said keyboard and to shift said ordinal complementary digit stops to operative relationship with respect to said accumulator actuator elements and said keyboard whereby to limit subsequent motion of their respective actuator elements to amounts proportional to the complementary values of the values set up on the keyboard, means operable by said primary subtraction control key for preventing each denominational element of the accumulator actuator from operating while values are set up on the keyboard, means for holding said primary subtraction control key in depressed position, a secondary subtraction control key, means operable by said secondary subtraction control key for releasing said accumulator actuator preventing means whereby to subtract the value set up on the keyboard from the accumulator by adding the complementary values determined by each element of the accumulator actuator receiving its maximum motion if its motion is not limited by

the complementary digit stops cooperating with the digit values set up on the keyboard, and means for releasing the primary subtraction control key from depressed position after the secondary subtraction control key has returned to normal non-depressed position.

12. In a calculating machine, a plurality of ordinal columns of digit keys, a multi-denominational register, a register actuator comprising a series of denominational elements each responsive to one ordinal column of digit keys, ordinal digit stop bars each articulately connected to an element of the register actuator and adapted to be intercepted by a depressed digit key to limit the motion of its respective actuator element to an amount proportional to the digit values of the keys depressed, an ordinal tens-complementary digit stop bar associated with the lowest denominational element of the register actuator, ordinal nines-complementary digit stop bars associated with all other denominational elements of the register actuator, a primary subtraction control key, means operable by said subtraction control key to replace said ordinal digit stop bars by their respective complementary digit stop bars to limit subsequent motion of the register actuator elements to amounts proportional to the complementary values of the digit keys depressed, means operable by said primary subtraction control key to detain each denominational element of the register actuator from operation while values are set up on the ordinal columns of digit keys, a secondary subtraction control key, means operable by said secondary subtraction control key to set all denominational elements of the register actuator in readiness for operation if they were not previously set by operation of the digit keys, and means operable by said secondary subtraction control key to release said register actuator detaining means, whereupon all elements of the register actuator will respond to add the complementary values of digit keys depressed or their respective complements of zero in denominational orders where no digit keys were depressed.

13. In a calculating machine, a keyboard, a multi-denominational accumulator, an accumulator actuator comprising a series of denominational elements each responsive to the keyboard, ordinal digit stops which limit the motion of the actuator elements to amounts proportional to the values set up on the keyboard, ordinal tens-complementary digit stops associated with the lowest denominational element of the accumulator actuator, ordinal nines-complementary digit stops associated with all other denominational elements of the accumulator actuator, a primary subtraction control key, means operable by said primary subtraction control key to replace said ordinal digit stops by their respective complementary digit stops to limit subsequent motion of the accumulator actuator elements to amounts proportional to the complements of values set up on the keyboard, means operable by said primary subtraction control key to detain each denominational element of the accumulator actuator from operation while values are set upon the keyboard, a secondary subtraction control key, means operable by said secondary subtraction control key to set all denominational elements of the accumulator actuator in readiness for operation if they were not previously set by operation of the keyboard, means operable by said secondary subtraction control key to release said accumulator actuator detaining means whereupon all elements of the accumulator actuator will respond to add

the complements of the values set up on the keyboard into the accumulator.

14. In a calculating machine, a plurality of ordinal columns of digit keys, a multi-denominational register, a multi-denominational register actuator responsive to said digit keys, a primary calculation control key, means operable by said primary calculation control key for detaining said register actuator from key responsive operation while values are set up on the digit keys, latching means for holding said primary calculation control key in depressed position subsequent to manual operation of said key, a secondary calculation control key, locking means to normally prevent operation of said secondary calculation control key, means operable by said primary calculation control key to unlock said locking means thereby to permit subsequent manual operation of said secondary calculation control key, said locking means thereafter serving to prevent said primary calculation control key from rising to normal non-depressed position until said secondary calculation control key has risen to normal non-depressed position, means operable by said secondary calculation control key for releasing said register actuator detaining means to permit said register actuator to respond to values set up on the digit keys, and means operable by said register actuator for unlatching said latching means to release said primary calculation control key so that it may rise from depressed position after said secondary calculation control key has been manually released from depressed position out of cooperating relation with said locking means.

15. In a calculating machine, a keyboard, an accumulator, an accumulator actuator responsive to said keyboard, a primary calculation control key, means operable by said primary calculation control key to detain said accumulator actuator from operation while values are set up on the keyboard, latching means to hold said primary calculation control key in depressed position, a secondary calculation control key, interlocking means for preventing depression of said secondary calculation control key when said primary calculation control key is in normal non-depressed position, means operable by said primary calculation control key for conditioning said interlocking means whereby to enable depression of said secondary calculation control key and subsequently to prevent the free rising of said primary calculation control key until said secondary calculation control key has risen to normal non-depressed position, means operable by said secondary calculation control key to release said accumulator actuator detaining means to permit said accumulator actuator to respond to values set up on the keyboard, and means operable by said accumulator actuator to unlatch said latching means, and release said primary calculation control key so that it may rise from depressed position after said secondary calculation control key has risen to normal non-depressed position out of cooperating relation with said interlocking means.

16. In a calculating machine, a primary control member, a secondary control member, a locking member which normally holds said secondary control member inoperable and having a hook portion in engageable relationship with said primary control member, means operable by said primary control member to move said locking member to render said secondary control member operable and to move said hook portion into engagement with said primary control member, a

latching means cooperating with said last means to hold said locking member in operative position whereby said hook portion holds said primary control member in operative position, and means operable in response to said secondary control member to unlatch said latching means, said secondary control member thereafter serving to obstruct the movement of said locking member whereby to prevent the return of said primary control member to normal inoperative position until said secondary control member has returned to normal inoperative position.

17. In a calculating machine, a primary control member, a notch on said primary control member, a secondary control member, a locking member, a lug on said locking member which normally holds said secondary control member inoperative, a hook portion on said locking member in engageable relationship with the notch on said primary control member, means operable by said primary control member to move said locking member whereby to move said lug away from said secondary control member to render it operable and simultaneously to move said hook portion to engage the notch on said primary control member to hold said primary control member in operative position, latching means cooperating with said last means for holding said locking member in operative position, and means operable in response to operation of said secondary control member to unlatch said latching means, said secondary control member thereafter serving to obstruct the movement of said lug on said locking member to prevent the return of said primary control member to normal inoperative position until said secondary control member has returned to normal inoperative position.

18. In a calculating machine, a plurality of ordinal columns of digit keys, a multi-denominational register, a multi-denominational register actuator, a plurality of laterally shiftable ordinal stop bars, digit stops on said stop bars which normally limit the motion of the actuator when intercepted by the depressed digit keys, complementary digit stops on said stop bars normally in ineffective position with respect to said digit keys, laterally shiftable supporting means for said stop bars, a subtraction control key, and means operable by said subtraction control key to shift said shiftable supporting means for moving said digit stops out of cooperative relationship with said digit keys and for moving said complementary digit stops into cooperative relationship with said digit keys.

19. In a power driven, key-responsive calculating machine having a multi-denominational accumulator, denominational orders of mechanism for actuating said accumulator, means for driving the denominational elements of said actuating mechanism, power means, a plurality of ordinal columns of digit keys, means operable by said digit keys for connecting said power means and said driving means, and digit stop bars cooperating with said digit keys for determining the digital actuation of said actuating mechanism in positive calculations; other normally ineffective complementary stop bars for determining the digital actuation of said actuating mechanism in negative calculations, a primary calculation control key, means operable upon depression of said primary calculation control key to prevent operation of said connecting means thereby making the machine key-set during subsequent operation of the digit keys, means operable by said primary calculation control key for shifting said

digit stop bars out of cooperating relationship with said digit keys and for shifting said normally ineffective complementary stop bars into cooperating relationship with said digit keys, means for holding said primary calculation control key in depressed position, a secondary calculation control key, means operable by said secondary calculation control key for engaging said connecting means and for simultaneously operating all denominational elements of the actuating mechanism irrespective of whether or not keys have been set in any or all of the ordinal columns of digit keys, and means for releasing said primary calculation control key whereby to return said digit stop bars and said complementary stop bars to their normal positions subsequent to the manual release of the secondary calculation control key.

20. In a calculating machine, a keyboard comprising a series of denominational columns of digit keys, a multi-denominational accumulator, a multi-denominational accumulator actuator responsive to said key board, stops to limit the maximum motion of each denominational element of the accumulator actuator to nine units except the lowest denominational element which may have a maximum motion of ten units, ordinal digit stops which limit the motion of the elements of the accumulator actuator according to the digit values set upon the keyboard, tens-complementary digit stops associated with the lowest denominational element of the accumulator actuator, ordinal nines-complementary digit stops associated with all other denominational elements of the accumulator actuator, a primary subtraction control key, a secondary subtraction control key, locking means for normally preventing operation of said secondary subtraction control key, means operable by said primary subtraction control key for replacing said ordinal digit stops by their respective complementary digit stops, means operable by said primary subtraction control key for detaining each denominational element of the accumulator actuator from operation while values are set up on the keyboard, means for holding said primary subtraction control key in depressed position subsequent to manual operation of said key, means operable by said primary subtraction control key for unlocking said locking means to permit subsequent manual operation of said secondary subtraction control key, means operable by said secondary subtraction control key for setting all denominational elements of the accumulator actuator in readiness for operation if not previously set by operation of the keyboard, means operable by said secondary subtraction control key for releasing said accumulator actuator detaining means whereby to subtract the value set up on the keyboard from the accumulator by adding the complementary values determined by each element of the accumulator actuator receiving its maximum motion if its motion is not limited by the complementary digit stops cooperating with the digit keys set up on the keyboard, said locking means being adapted to release the primary subtraction control key from depressed position only after the secondary subtraction control key has returned to non-depressed position.

21. In a calculating machine, a plurality of ordinal columns of keys corresponding to the digits 1 to 9, inclusive, a multi-denominational register, a multi-denominational register actuator for each denominational element of which is re-

sponsive to one ordinal column of digit keys, ordinal digit stop bars which limit the motion of the actuator; a tens-complementary digit stop bar associated with the lowest denominational element of the register actuator, ordinal nines-complementary digit stop bars associated with all other denominational elements of the register actuator that are responsive to a column of digit keys, a primary subtraction control key, means for holding said primary subtraction control key in depressed position subsequent to manual operation of said key, means operable by said primary subtraction control key for replacing said ordinal digit stop bars by their respective complementary digit stop bars, means operable by said primary subtraction control key for detaining each denominational element of the register actuator from operation while values are set up on the ordinal columns of digit keys, a secondary subtraction control key, means for preventing manual operation of said secondary subtraction control key unless said primary subtraction control key is in depressed position, means operable by said secondary subtraction control key for setting all denominational elements of the register actuator in readiness for operation if not previously set by operation of the digit keys in their respective ordinal columns, means operable by said secondary subtraction control key for releasing said register actuator detaining means to subtract the value set up on the ordinal columns of digit keys from the register by adding the complementary values corresponding to the digit keys depressed and adding "9's" in all columns where no digit key is depressed and "10" in the lowest denominational column if no key was depressed in that column, and means for releasing the primary subtraction control key from depressed position after the secondary subtraction control key has returned to non-depressed position.

22. In a calculating machine, a plurality of ordinal columns of digit keys, a multi-denominational register, a multi-denominational register actuator each denominational element of which is responsive to one ordinal column of digit keys, a primary subtraction control key, means for holding said primary subtraction control key in depressed position subsequent to manual operation of said key, means operable by said primary subtraction control key for detaining each denominational element of the register actuator from operation while values are set up on the ordinal columns of digit keys, a secondary subtraction control key, interlocking means for preventing manual operation of said secondary subtraction control key unless said primary subtraction control key is in depressed position, means operable by said secondary subtraction control key for setting all denominational elements of the register actuator in readiness for operation if not previously set by operation of the digit keys in their respective ordinal columns, means operable by said secondary subtraction control key for releasing said register actuator detaining means to cause operation of all elements of the register actuator, and means operable by said register actuator for releasing the means for holding said primary subtraction control key, said interlocking means thereafter serving to prevent said primary subtraction control key from rising to normal position until said secondary subtraction control key has returned to non-depressed position.

23. In a calculating machine, a plurality of or-

dinal columns of digit keys, a multi-denominational register, a multi-denominational register actuator each denominational element of which is responsive to one ordinal column of digit keys, a primary subtraction control key having a notch therein, a secondary subtraction control key, interlocking means having a lug thereon which normally holds said secondary subtraction control key inoperable, and having a hook portion in engageable relationship with said notch, means operable by said primary subtraction control key for moving said interlocking means whereby to move said lug away from said secondary subtraction control key to render it operable and simultaneously to move said hook portion to engage said notch in said primary subtraction control key to hold it in operative position, means operable by said primary subtraction control key for detaining each denominational element of the register actuator from operation while values are set up on the ordinal columns of digit keys, latching means cooperating with said interlocking means for holding it in operative position, means operable by said secondary subtraction control key for setting all denominational elements of the register actuator in readiness for operation if not previously set by operation of the digit keys in their respective ordinal columns, means operable by said secondary subtraction control key for releasing said register actuator detaining means to cause operation of all elements of the register actuator, means operable by said register actuator for unlatching said latching means, said secondary subtraction control key thereafter serving to obstruct the movement of said lug on said interlocking means to prevent the return of said primary subtraction control key to normal inoperative position until said secondary subtraction control key has returned to normal inoperative position.

24. In a calculating machine having a multi-denominational register and a multi-denominational register actuator, calculation control mechanism for determining the digital actuation of said actuator for positive and negative types of calculation, comprising a plurality of ordinal columns of operable digital keys, a plurality of pairs of digit stops, one pair being associated with each key in said column, one digit stop in each of said pair being adapted to cooperate with the associated key for positive calculation operations, and the other digit stop in each said pair being adapted to cooperate with the associated key for negative calculation operations, means for mounting said stops for movement transversely of the columns of keys between positions for positive and negative calculation operations and for movement of the pairs of stops longitudinally of the respective columns of keys to cooperate with any operated key therein during calculating operations, and means for moving all of said stops transversely of the columns of keys between said positions for positive and negative calculation operations to predetermine the type of calculation operation to be performed by said machine.

25. In a calculating machine, a plurality of ordinal columns of digit keys, an accumulator, a plurality of ordinal key-responsive accumulator actuator elements, a depressible primary calculation control key, means settable by said primary calculation control key for preventing said accumulator actuator elements from responding to the operation of said digit keys, means for holding said primary calculation control key in

depressed position, a depressible secondary calculation control key, means operable by said secondary calculation control key for releasing said settable means, and means operable by said secondary calculation control key for releasing said primary calculation control key from depressed position after said secondary calculation control key has returned to normal non-depressed position.

26. In a normally key-responsive calculating machine having digital control keys, an accumulator, and mechanism for actuating said accumulator in response to depression of said keys; primary control means movable from an initial position to condition the key responsive mechanism for key-set actuation, secondary control means operable to cause the operation of the actuating mechanism and the restoration of said primary control means to its initial position whereby automatically to recondition the machine for key responsive actuation, and means for insuring the operation of said primary control means before said secondary control means can be operated, the operation insuring means comprising a bar, a lug on said bar normally obstructing the motion of said secondary control means, and means operable by said primary control means for moving said bar and removing said lug from the path of motion of said secondary control means.

27. A normally key-responsive calculating machine capable of key-set operation, comprising digital control keys, an accumulator, actuating mechanism for said accumulator, means operable in response to depression of said keys for initiating the operation of said actuating mechanism, primary control means manually movable from an initial position to render ineffective the operation initiating means of said actuating mechanism and to condition the machine for key-set operation, secondary control means manually operable to institute operation of said actuating mechanism, and means operable in response to operation of said secondary control means for restoring said primary control means to its initial position and reconditioning the machine for key-responsive operation.

28. A normally key-responsive calculating machine capable of key-set operation, comprising digital control keys, an accumulator, actuating mechanism for said accumulator, means operable in response to depression of said keys for initiating the operation of said actuating mechanism, primary control means manually movable from an initial position to render ineffective the operation initiating means of said actuating mechanism and to condition the machine for key-set operation, secondary control means manually operable to institute operation of said actuating mechanism, means operable in response to operation of said secondary control means for restoring said primary control means to its initial position and reconditioning the machine for key-responsive operation, and locking means for preventing operation of said secondary control means while said primary control means is in its initial position.

29. In a normally key-responsive calculating machine having digital control keys, an accumulator, and mechanism for actuating said accumulator in accordance with the values of and in response to the depression of said keys; normally inactive control means manually operable to condition the key-responsive mechanism for key-set actuation and condition said mechanism to actuate said accumulator in accordance with the complemental values of the keys depressed, and

means manually operable subsequently to the operation of said normally inactive control means to cause operation of said mechanism and return of said normally inactive control means to inactive condition for automatically reconditioning the machine for key-responsive actuation.

30. In a calculating machine having an accumulator, denominational orders of mechanism for actuating said accumulator responsive to key action, keys for operating the actuating mechanism, and normally effective means for determining the digital actuation of said accumulator by said actuating mechanism in accordance with the values of the keys depressed; a first calculation control key, a second calculation control key, means settable by said first calculation control key for maintaining the value keys in depressed key-set position and preventing operation of said actuating mechanism responsive thereto, whereby to condition the machine for key-set operation, normally ineffective means for determining the digital actuation of said accumulator by said actuating mechanism in accordance with the nines complements of the keys depressed in all denominational orders except the units order, and in accordance with the value of the ten's complement of the key depressed in the units order, means operable by said first calculation control key for rendering said normally effective means ineffective and said normally ineffective means effective, means operable by said second calculation control key to release the means settable by said first calculation control key for causing the operation of said actuating mechanism to add the complementary values of the keys depressed, and means responsive to said second calculation control key for returning said normally ineffective means to ineffective condition and for cooperating with the means operable by said second calculation control key to recondition said actuating mechanism for key-responsive operation.

31. In a calculating machine having an accumulator, denominational orders of mechanism for actuating said accumulator responsive to key action, keys for operating said actuating mechanism, normally effective means for determining the digital actuation of said actuating mechanism in accordance with the values of the keys depressed in key-responsive operation, a primary calculation control key, means settable by said primary calculation control key for maintaining said keys in depressed key-set position and preventing operation of said actuating mechanism responsive thereto, normally ineffective means for determining the digital actuation of said actuating mechanism in accordance with the complemental values of the keys depressed in key-set operation, means operable by said primary calculation control key for rendering said normally effective means ineffective and said normally ineffective means effective, a secondary calculation control key, means operable by said secondary calculation control key to release the means settable by said primary calculation control key for causing the operation of said actuating mechanism to add the complementary values of the keys depressed, and means responsive to said secondary calculation control key for returning said normally ineffective means to ineffective condition and for cooperating with the means operable by said secondary calculation control key to recondition said actuating mechanism for key-responsive actuation.

32. In a key responsive calculating machine, a

plurality of ordinal columns of digit keys, a multi-denominational accumulator, a multi-denominational accumulator actuator, means for driving said accumulator actuator responsive to key action, power means, key-controlled means for connecting said power means and said driving means, and digit stop bars cooperating with said digit keys for determining the digital actuation of said accumulator actuator in positive calculations, other normally ineffective complementary stop bars for determining the digital actuation of said accumulator actuator in negative calculations, a first calculation control key, means settable by said first calculation control key for preventing connection between said power means and said driving means thereby making the machine key-set during subsequent operation of the digit keys, means operable by said first calculation control key for shifting said digital stop bars out of cooperating relationship with said digit keys and for shifting said normally ineffective complementary stop bars into cooperating relationship with said digit keys, means for releasably holding said first calculation control key in depressed position, a second calculation control key, means operable by said second calculation control key for operating said connecting means and for simultaneously operating all denominational elements of the accumulator actuator irrespective of whether or not keys have been set in any or all of the ordinal columns of digit keys and for returning the machine to key-responsive operation, and means responsive to said second calculation control key for releasing said first calculation control key whereby to return said digit stop bars and said complementary stop bars to their normal positions.

33. In a calculating machine, a keyboard having a plurality of rows of individually operable keys; a totalizer having a plurality of individually operable digit wheels, one for each row of keys; rack means for operating said wheels individually; a stop bar unit connected to and movable with each of said rack means, each unit having a pair of stop members movable together and each stop member formed with a group of stops which by engagement with operated keys determine the extent of movement of the digit wheels; and means by which the keys of said keyboard may be caused to cooperate selectively with the group of said stops on either of the members of each unit in limiting the extents of movement of said units, the stops of one said stop member of each unit cooperating with any operated key of the related row to cause the movement of the related digit wheel an extent corresponding to the number represented by the key that is operated, and the stops of the other of said stop member of each unit also cooperating with any operated key of the related row to cause the movement of the related digit wheel an extent corresponding to a complement of the number represented by the key that is operated.

34. In a calculating machine, a totalizer having digit wheels; a keyboard having individually operable keys which are selectively operable to initiate the successive entry in said totalizer of numbers corresponding to items of the calculation; stop bar units mounted for collective bodily movement between two positions, there being one stop bar unit for each digit wheel, each said stop bar unit being mounted for individual movement in directions crosswise of the direction of said bodily movement; means interacting with each stop bar unit for operating a related digit wheel

depending upon the extent of individual movement of that stop bar unit in one direction; each key of said keyboard having a stop which normally clears its related stop bar unit but moves into a position to control the travel of said related stop bar unit when the key is operated; each stop bar unit having two rows of spaced abutments, with the rows extending in the direction of individual movement of that unit, the abutments of one row being disposed to engage an operated related key when said stop bar units collectively are in one of their said positions, and the other row being disposed to engage said operated related key when said stop bar units collectively are in the other of their said positions, said abutments in each row being spaced to determine the extent of possible individual movement of that stop bar unit before engaging a stop of an operated key for that stop bar unit; and means for causing individual movements of the stop bar units respectively related to the extents permitted by the stops of said related operated keys when a number initiated by the selective operation of the keys of said keyboard is to be entered in said totalizer.

35. In a calculating machine, a totalizer having a plurality of individual digit wheels disposed side by side; a plurality of stop bar units, one for each of the digit wheels, disposed side by side; means interacting between each stop bar unit and its related digit wheel for operating the latter in a rotary direction an extent proportional to the extent of movement of that stop bar unit, each stop bar unit having two rows of abutments with the rows running in the direction of movement of that stop bar unit; a keyboard having a row of individually operable keys related to each stop bar unit, which are selectively operable to initiate the successive entry in said totalizer of numbers corresponding to items of the calculation; stop means normally out of the path of movement of the stop bar units but movable into the path of movement of a related stop bar unit by the depression of the keys; means mounting said stop bar units for collective bodily movement and enabling the rows of said abutments to be collectively shifted, whereby selectively to position the rows of abutments of each stop bar unit for engagement with the related stop means for determining the extent of movement of the stop bar unit in proportion to the particular key operated, the extent of movement permitted by one row of abutments of each unit representing the complement of that permitted by the abutments of the other row of the same unit; means for moving said stop bar units in a direction to carry said abutments toward said stop means; and means for returning all of said stop bar units to corresponding initial positions.

36. In a calculating machine, a totalizer having a plurality of individual digit wheels disposed side by side; a plurality of stop bar units, one for each of the digit wheels, disposed side by side; means interacting between each stop bar unit and its related digit wheel for operating the latter in a rotary direction an extent proportional to the extent of movement of that stop bar unit, each stop bar unit having two rows of abutments with the rows running in the direction of movement of that stop bar unit; a keyboard having a plurality of individually operable keys which are selectively operable to initiate the successive entry in said totalizer of numbers corresponding to items of the calculation, said keys having stop means which are effective when the keys are operated

and which are engageable selectively by one row or the other of the abutments on said stop bar units, for determining the extent of movement of the stop bar units according to the particular key operated, the extent of movement permitted by one row of abutments of each unit representing the complement of that permitted by the abutments of the other row of the same stop bar unit; means for mounting the stop bar units for collective shifting movement to bring either row of abutments of each unit in alignment with the stop means on the respectively related, operated keys; means normally urging all of the stop bar units to a position in which the cooperation of the abutments and the stop means allows the stop bar units to move extents corresponding to the value of the keys operated; subtraction means for collectively shifting the stop bar units from their normal position to a position in which the cooperation of the abutments and the stop means allows the stop bar units to move extents corresponding to the complement of the keys operated; means for moving each stop bar unit in a direction to carry the abutments toward said stop means; and means for returning all of said stop bar units to corresponding initial positions.

37. In a device of the class described, the combination of a row of value-representing key-operated stop members which are normally in an ineffective position but which are moved to an effective position when operated; an operable member having side by side thereon two rows of abutments, the abutments of one row being so spaced along the operable member in the direction of its movement that cooperation of an abutment of that row with an operated stop member controls the movement of the operable member to an extent which represents the value of the stop member, and the abutments of the other row being so spaced along the operable member in the direction of its movement that cooperation of an abutment of said other row with an operated stop member controls the movement of the operable member to an extent which represents the complement of the value of the operated stop member; means for mounting said rows of abutments for movement relative to said row of stop members; and means for shifting the mounting means to bring either row of abutments into alignment with said stop members to enable the same stop members to control the extent of movement of the operable member according to the value of the stop members or according to the complement of the value of the stop members.

38. In a device of the class described, the combination of a row of value-representing key-operated stop members which are normally in an ineffective position but which are moved to effective position when operated; an operable member having side by side thereon two rows of abutments, the abutments in one row being so spaced along the operable member in the direction of its movement that cooperation of an abutment of that row with an operated stop member controls the movement of the operable member to an extent which represents the value of the stop member, and the abutments in the other row of abutments being so spaced along the operable member in the direction of its movement that cooperation of an abutment of said other row with an operated stop member controls the movement of the operable member to an extent which represents the complement of the value of the operated stop member; means for mounting said

rows of abutments for movement relative to said row of stop members, said mounting means normally supporting said operable member for performing addition; with the row of abutments in alignment with the stop members to control the extents of movement of the operable member to represent the values of the stop members; and subtraction control means for shifting the operable member to bring the other row of abutments into alignment with the stop members to enable the same stop members to control the extent of movement of the operable member to represent the complement of the value of the stop members, for performing subtraction.

39. In a device of the class described, the combination of a row of value-representing key-operated stop members which are normally in an ineffective position but which are moved to an effective position when operated; an operable member having side by side thereon two rows of abutments, the abutments of one row being so spaced along the operable member in the direction of its movement that cooperation of an abutment in that row with an operated stop member controls the movement of the operable member to an extent representing the value of the stop member, and the abutments of the other row being so spaced along the operable member in the direction of its movement that cooperation of an abutment of said other row with an operated stop member controls the movement of the operable member to an extent representing the complement of the value of the operated stop member; means for mounting said operable member for movement relative to said stop members, the mounting means supporting the operable member normally for performing addition, with the row of abutments, which in cooperation with the stop members control the extents of movement of the operable member to represent the values of the stop members, in alignment with said stop members; subtraction control means for shifting said mounting means for the operable member to bring the other row of abutments into alignment with said stop members to enable the same stop members to control the extent of movement of the operable member to represent the complement of the value of the stop members; and means to restore said mounting means to normal position automatically at the end of a subtraction operation.

40. In a device of the class described, the combination of a row of value-representing key-operated stop members which are normally in an ineffective position but which are moved to an effective position when operated; an operable member having side by side thereon two rows of abutments, the abutments of one row being so spaced along the operable member in the direction of its movement that cooperation of an abutment of that row with an operated stop member controls the movement of the operable member to an extent which represents the value of the stop member, and the abutments of the other row being so spaced along the operable member in the direction of its movement that cooperation of an abutment of said other row with an operated stop member controls the movement of the operable member to an extent representing the complement of the value of the operated stop member; means for mounting the operable member for movement relative to said stop members; means yieldingly positioning the mounting means normally in a position to bring into alignment with the stop members the abutments which con-

33

trol the extents of movement of the operable member to represent the values of the stop members, for performing addition; subtraction control means for shifting the mounting means to bring into alinement with said stop members the other row of abutments to enable the same stop members to control the extent of movement of the operable member to represent the complement of the value of the stop members for per-

34

forming subtraction; means for latching said mounting means in the position to which it is set for subtraction; and means to release the latch automatically at the end of a subtraction operation to allow the mounting means to return the stop members to their normal, addition position.
